UNITED STATES PATENT OFFICE.

CHARLES E. BRADLEY, OF MONTCLAIR, NEW JERSEY, AND JOSEPH G. COFFIN, OF HEMPSTEAD, NEW YORK, ASSIGNORS TO GENERAL RUBBER COMPANY, A CORPORATION OF NEW JERSEY.

SPRAYER.

Original application filed December 7, 1921, Serial No. 520,505. Divided and this application filed April 3, 1922. Serial No. 549,359.

To all whom it may concern:

Be it known that we, CHARLES E. BRADLEY and JOSEPH G. COFFIN, both citizens of the United States, and residing at Montclair, in the county of Essex and State of New Jersey, and Hempstead, Long Island, in the county of Nassau and State of New York, respectively, have invented a certain new and useful Sprayer, of which the following is a full, clear, and exact description.

This invention relates to a sprayer, more particularly to a sprayer of the type disclosed in our copending application Serial No. 520,505, filed December 7, 1921, now Patent No. 1,428,526, of which this is a division.

In our application above mentioned there is disclosed an apparatus for uniformly distributing finely divided particles of rubber latex in a drying medium to thereby drive off the contained moisture in the latex, while the dry particles of latex settle by gravity to a collecting surface from which they may be removed as desired. The ordinary types of compressed air sprayers when used for the purpose of spraying the latex, are open to several objections, one of which is that they are not economical for the reason that in compressing the air used in spraying considerable heat is developed which is lost, and during the spraying operation the expansion of the air causes a considerable drop in temperature, which must be overcome by either increasing the quantity of the drying medium used or heating it to a higher temperature. Another objection is that the particles as sprayed by a compressed air sprayer vary considerably in size and include a proportion of extremely fine dust-like particles which when dry do not readily separate out by gravity from the drying medium, but tend to be carried along therewith. It is not practicable to recover such extremely fine particles except by the use of relatively expensive additional apparatus. Moreover the particles as sprayed by compressed air cannot be distributed in the drying medium with the uniformity desired.

An object of our invention is to provide an improved and economical sprayer for latex or similar material.

Another object is to provide a sprayer in which the sprayed particles will be of relatively uniform size and uniformly distributed as compared with pressure or compressed air sprayers. 55

Still another object is to provide a sprayer of the rotatable disk type in which the fluid will be delivered to the disk with the least possible disturbance. 60

A further object is to provide a sprayer of the disk type in which the fluid to be sprayed will be effectively protected against 65 heating until delivered to the disk.

For a detailed disclosure of the invention reference is had to the accompanying specification and drawing, in which latter:

Fig. 1 represents a vertical section 70 through the sprayer;

Fig. 2 is an enlarged detail of the discharge nozzle; and

Fig. 3 is a similar detail illustrating a 75 slightly modified form of nozzle.

Referring to the drawings the numeral 1 represents the sprayer generally, which latter may be secured to any suitable support 2, such as the ceiling of a room or chamber in which the sprayer is to be mounted. An enclosed supporting frame or casing 3 is provided, which for convenience in assembly may be made in two sections secured together by the bolts 4. This casing is of an elongated form, and is provided with a tapered or reduced portion 5 at its lower end, while at its sides are formed reinforcing ribs 6 to give rigidity to the casing. A shaft 7 extends through the casing with its ends projecting through each end of the latter, and within the casing the shaft is journaled in bearings 8 and 9. The upper projecting end of the shaft is provided with a pulley 10 by which the shaft may be rotated, but it is evident that any other suitable form of drive, such as gearing, may be substituted. A spraying disk 11 is secured to the lower projecting end of the shaft, which disk is preferably formed tapering towards its edge as shown, and preferably with a flat, smooth upper surface. This disk may be made of any suitable non-corrod़ing alloy or of nickel plated steel. Surrounding the lower projecting portion of the shaft and secured to the casing 3, is a 100 tapered tube 12 which extends to a point 105

closely adjacent the disk 11, and forms one wall of a discharge passage.

In order to prevent drip of oil from the bearings on the disk 11 during operation the 5 shaft 7 is provided with a series of annular grooves 13 which form between them a series of ridges adapted to centrifugally project any oil drip, the discharged oil being collected in a catch-basin 14 at the 10 bottom of casing 3, from which it may be withdrawn in any suitable manner, as by the pipe 15. Surrounding the casing 3 and spaced from it to provide a latex chamber 16 is a cooling jacket formed by an outer wall 15 17 and an inner wall 18. These walls are joined at their upper ends, and the cooling jacket is secured to the casing 3 by bolts 19. At the lower end of the cooling jacket the walls 17 and 18 are also joined, the lower 20 portion of the jacket being formed of a frusto-conical shape as shown at 20, and the jacket is steadied against vibration by means of the screw rods 21 bearing against the upper end of the tube 12. A nozzle 22 25 is adjustably secured in the lower end of the cooling jacket, as by means of screw threads, and held in adjusted position by the lock nut 23, this nozzle forming in connection with the tapered tube 12 a discharge outlet 30 from the latex chamber 16 to the exposed surface of the disc 11, this outlet being adjacent to but independent of the shaft 7. A supply pipe 24 for the latex or other material to be sprayed communicates with 35 the upper end of the chamber 16, and a supply pipe 25 for the cooling agent, such as water, passes down through the latex chamber and is tapped into the lower end of the cooling jacket, while at the upper end of the 40 jacket an exhaust pipe 26 for the cooling agent is provided.

It is important, owing to the high speed at which the disk is rotated, that the latex be led from the chamber 16 onto the disk 45 with as little disturbance as possible, as otherwise the latex tends to be thrown off the disk before it has reached the edge and attained the desired horizontal speed. The inner wall of the nozzle 22 is therefore made 50 of a rounded flaring or horn shape at its lower end, as shown at 27. The horizontal length of the passage between this horn-shaped end and the disk may be relatively short as shown in Fig. 2, or the flaring end 55 of the nozzle 28 may be laterally extended to some distance, as shown at 29 in Fig. 3, this horizontal length preferably varying from about $\frac{1}{2}$ of an inch to $\frac{3}{4}$ of an inch.

In operation, the disk is rotated at a relatively high speed by means of the pulley 10, and water is first supplied through the pipe 24 to chamber 16, and discharged through nozzle 22 on the disk 11. As the disk rotates in a chamber filled with a rather 60 highly heated drying medium, if latex were

supplied at the beginning to the disk it would tend to coagulate and burn thereon but by first admitting the water to the sprayer disk it is cooled sufficiently to permit the subsequent gradual substitution of latex without injury to the latter. By adjusting the nozzle 22 toward and from the disk any desired regulation of the flow of latex may be obtained. As the latex flows outwardly on the uncovered or exposed surface of the revolving disk it acquires a high radial velocity as well as a high circumferential one, and as it reaches the edge of the disk has a resultant velocity of about one and four tenth times the rim speed of the disk. A rim speed of about 300 miles per hour has been found to be suitable for the disk when spraying latex, but it is evident that this speed may be varied as desired. By reason of the relative movement between the sprayer disk and the nozzle 22 any tendency of the outlet to become clogged is avoided. As the latex is uniformly discharged from all portions of the periphery of the disk it is evident that a very uniform distribution in the drying medium can be secured, and it has also been found that the variation in the size of the particles is relatively small as compared with those obtained by compressed air spraying, this variation not being ordinarily greater than from a unit diameter to ten times the diameter. The formation of extremely small dust-like particles, such as those smaller than 10 microns, which are difficult to recover when dry, is also practically obviated. As latex is easily affected by heat, which tends to coagulate it, it is desirable that the supply chamber or passage by which the latex is conducted to the discharge nozzle 22 be protected from the heat of the drying medium in which it is disposed, and the cooling jacket 17, 18 effectively performs this function. Rubber latex is also extremely sensitive to agitation and shock, and therefore as pointed out in the objects it is essential that it be handled with great care during the spraying operation and delivered to the spraying disc with as little disturbance as possible in order to prevent coagulation and consequent clogging of the apparatus. For this reason the latex discharge outlet formed by the tube 12 and nozzle 22 is provided, by which construction any contact of the latex with the rapidly revolving shaft 7 is prevented. If the latex were allowed to contact with the shaft at any time during its flow to the disc 11 the consequent friction and centrifugal action would quickly cause coagulation of the latex and clogging of the lower portion of the latex chamber and discharge outlet. The frame or casing 3 with its reinforcing ribs 6 effectively prevents undesirable vibration due to the high speed at which the disk is rotated.

While the apparatus has been described as applied to the spraying of latex, for which it is particularly designed, it is evident that it is of general application, and 5 may be used for spraying other liquids. While a detailed disclosure of one embodiment of the invention has been made, it is evident that changes may be made therein, and it is not desired that the invention shall 10 be limited otherwise than as set forth in the appended claims.

Having thus described our invention, what we claim and desire to protect by Letters Patent is:

15 1. A sprayer for latex or other liquid comprising a smooth, unobstructed disc, means for rotating the same, and means for discharging the liquid centrally of the disc comprising a tubular wall terminating 20 closely adjacent the disc, and a surrounding adjustable wall concentric therewith and co-acting with the disc to form an adjustable outlet.

25 2. A sprayer for latex or other liquid comprising a shaft, means for rotating the same, a disc on the end of the shaft, a liquid chamber having an annular outlet independent of and surrounding said shaft adjacent the disc, and adjustable means for varying 30 the rate of discharge from said outlet.

35 3. A sprayer for latex or other liquid comprising a shaft, means for rotating the same, a disc on the end of said shaft, a liquid chamber surrounding and spaced from said shaft throughout its length and having an outlet adjacent said disc, means for varying the distance of said outlet from the disc, and heat insulating means surrounding said chamber.

40 4. A sprayer for latex or other liquid comprising a rigid frame, a vertical shaft journaled in said frame adjacent its ends, means at the upper end of the shaft for rotating it, a disc secured to the lower end of 45 the shaft and having a flat, unobstructed surface, an annular liquid chamber surrounding and spaced from said shaft and having an open lower end spaced from said disc to form a discharge opening, and means 50 for varying the size of said opening.

5. A sprayer comprising a rotatable shaft, a spraying disc secured thereto and having

an uncovered upper surface, means for discharging fluid on the uncovered surface of said disc symmetrically of said shaft and 55 on the same side of the disc as said shaft, and means for preventing contact of said fluid with rotating parts prior to its discharge on said disc.

6. A latex sprayer comprising a shaft, 60 means for rotating the same, a spraying disc secured to an end of the shaft, means for centrally and smoothly discharging latex or other fluid on the disc including a nozzle surrounding the shaft adjacent the disc, 65 said nozzle having a rounded flaring end, means whereby the nozzle may be adjusted toward and from the disc, and means for shielding the latex from moving parts prior to its discharge on the disc. 70

7. A latex sprayer comprising a shaft, means for rotating the same, a spraying disc secured to an end of the shaft, means for centrally and smoothly discharging latex or other fluid on the disc including a 73 nozzle surrounding the shaft adjacent the disc, said nozzle having a rounded and horizontally extended flaring end, means whereby the nozzle may be adjusted toward and from the disc, and means for shielding the 80 latex from rotating parts prior to its discharge on the disc.

8. A latex sprayer comprising an enclosed casing, a shaft extending therethrough and projecting above and below the same, bearings in said casing for the shaft, means for rotating the shaft, a spraying disc secured to the lower end of the shaft, means for delivering latex or other fluid centrally of said disc comprising a tube secured to said 85 casing and extending around said shaft end to a point adjacent the disc, and a discharge nozzle surrounding said tube and adjustable with respect to the disc, and means for preventing oil drip from the bearings on said 90 disc comprising a series of ridges on the shaft below the bearings and a catch basin in the casing adjacent said ridges. 95

Signed at New York, in the county of New York, and State of New York, this 28 day 100 of March, 1922.
